UNITED STATES PATENT OFFICE.

GEORGE SUTCLIFFE, OF CHICAGO, ILLINOIS, ASSIGNOR OF ONE-HALF TO GEORGE T. WILLIAMS, OF CHICAGO, ILLINOIS.

INCINERATOR.

Application filed August 3, 1923. Serial No. 655,399.

To all whom it may concern:

Be it known that I, GEORGE SUTCLIFFE, subject of the King of Great Britain and Ireland, and a resident of Chicago, in the county of Cook and State of Illinois, have invented certain new and useful Improvements in Incinerators, of which the following is a specification.

This invention relates to improvements in incinerators and more particularly to furnaces used in dwellings, apartment buildings, and hotels, for consuming garbage and refuse. These devices are also frequently used for the heating of water for domestic purposes.

The object of the invention is to provide a practical construction for an incinerator, calculated to overcome a number of disadvantages present in such devices as heretofore constructed and erected, so far as I am familiar with the art.

An incinerator is ordinarily erected in the basement of a building with a chute leading thereto and having doors at the different floors through which the refuse is dumped. The usual equipment provides also for a smoke pipe leading from the incinerator to the chimney for carrying off the products of combustion, the air supply being drawn from the basement, through a damper in the ash door, in the same manner as in the usual furnace construction. There is ordinarily provided no communication between the chimney and the refuse chute so that the latter is practically a dead air space in which the odors accumulate. This condition is further aggravated by the falling masses of refuse which creates a pressure tending to force the air through the doors, thus creating an unwholesome and exceedingly obnoxious source of annoyance.

As will be presently pointed out, the chief purpose of the incinerator, herein disclosed, is to create a positive draft in the chute by an improved arrangement of flues, whereby the air pressure in the chute is always less than atmospheric, thus avoiding any possibility of a back pressure such as would tend to expel the air into the rooms above.

50 In the drawings:

Figure 1 is a view in longitudinal vertical section through the incinerator.

Figure 2 is a view in vertical section taken on line 2, 2 of Figure 1.

Figure 3 is a view in horizontal section taken on line 3, 3 of Figure 1, and

Figure 4 is a detailed view in side elevation of the gate operating lever.

As hereinbefore suggested, the general design of the incinerator resembles somewhat that of a furnace, being preferably constructed of brick work substantially as follows: The four upright walls are erected upon the floor or foundation, and in rectangular form, and consists of a front wall 1, a rear wall 2, side walls 3, 3, and a top wall 4, which form the outer shell of the incinerator.

Spaced inwardly from one of the side walls 3, the left hand wall (Figure 2) is 70 an inner vertical wall 5, extending from the floor to the top wall 4, and forming between it and the outer side wall, a comparatively narrow chamber or flue, which will be hereinafter described.

The space between the inner vertical wall 5 and opposite outer wall 3, and extending from the front to the rear wall, may be roughly divided into the forward combustion zone 6, and the rear drying zone 7, the former having an arched roof 8, extending transversely thereover. A grate 9 is located in the combustion zone, and supports the fuel bed 10. The space below the grate forms the ash pit 11. In the front wall 1 are provided the usual fire and ash doors 12 and 13. At the rear of the ash pit is a transverse wall 14, forming a support for the rear of the grate 9, and the forward portion of a rearwardly and upwardly curving 80 wall, known as the drying hearth 15, which terminates in substantially tangential relation with the rear wall 2, and acts as a forwardly inclined bottom wall for the refuse chute 16, at the rear of the incinerator. The refuse chute is a vertical passage formed of brick which extends upwardly and serves the floors above, each apartment, suite, or room as the case may be, having a door 16 located at a convenient place in the wall of 100 the kitchen, which is opened to receive the refuse.

At the lower end of the chute 16, and at the point where the same enters the rear or drying zone 7, of the incinerator is mounted a swinging damper or gate 17, supported upon a horizontal shaft 18 extending through one of the side walls. Mount-

ed at the end of the shaft exterior of the incinerator is an operating lever 19 consisting of two arms arranged at 90° apart. One of the arms serves as a hand lever, and 5 normally extends downwardly, while the other and normally horizontal arm carries a counter weight 20. The gate in closed position extends obliquely across the bottom of the chute 16, its lower edge bearing 10 against the curved surface of the drying hearth 15.

In the back wall of the chute 16, and at a distance above the lower end thereof, there is an opening 21, having a grating 22, therein, said opening forming the inlet to a flue 23, extending downwardly at the rear of the incinerator, and preferably exterior to the rear wall 2. As clearly shown in Figure 2, the flue follows an oblique direction from 15 the opening 21 to the top of the furnace and thence continues in a vertical direction to the floor at the rear right hand corner. The lower end of the vertical flue 23 is connected with a horizontal flue or duct 24, 20 which passes forwardly underneath the floor or bottom of the incinerator, to a point below the front wall 1. At this point the flue 24 divides into branches 25, 25, one extending upwardly through the front wall, 25 and terminates in an opening 26 on one side of the ash door 13, and the other extending laterally and then upward, terminating 30 in a like opening 26 on the opposite side of the ash door. These openings communicate with the ash pit 11.

In the wall 5 of the combustion zone 6, and near the forward end, is an outlet opening 27 which communicates with the vertical space 28 between the said wall 5 and the 40 adjacent outer wall 3. This space may be occupied by heating coils for heating water for domestic purposes. As clearly shown in Figure 3, the wall 5 joins the transverse wall 14, so that the space 28 communicates 45 at its lower end with a larger space 29, extending the full width of the incinerator, below the drying hearth 15. Projecting into the space below the drying hearth, and from the left hand side wall 3 is a transverse baffle wall 30, extending parallel to and spaced rearwardly of the wall 14. This wall terminates short of the opposite side wall 3, thereby forming an additional passage or duct 31, and converting the space below the hearth 55 into a circuitous or S-shaped passage. At the end of the rearmost passage 31, is an opening communicating with the base of a chimney or smoke pipe 32, shown as extending vertically upward just to the left of the 60 chute 16 (Figure 2). The chimney manifestly communicates with the atmosphere above the roof of the building and the same principle of draft is applicable as in the ordinary heating furnace.

65 The action of the incinerator will be un-

derstood from the following: In the first place it is to be understood that a fire is maintained in the fire-box either continuously as is customary in large buildings, or periodically, as the case may be. Normally, the gate 17 is held in closed position by the counter weight 20 and swung into open position by the attendant, at certain intervals, say, once or twice a day, depending on the accumulation of refuse to be consumed. The refuse, as it is emptied into the chute from the different floor levels, is retained at the bottom of the chute by the gate, until the attendant swings the gate forwardly into open position. This allows the refuse and 75 garbage to become partially dried, and the excess liquid to drain off. When the gate is swung open, this accumulation of partially dried refuse is delivered onto the drying hearth 15 where it is gradually reduced to 80 ashes by the heat, the combustibles being consumed and carried off with the other products of combustion. From time to time the ash accumulations are raked forwardly onto the fuel bed, thus keeping the hearth 85 clean.

The products of combustion are carried beneath the drying hearth through the passages 29 and 31, the heat being utilized for maintaining the hearth 15 at a high temperature, thus promoting the drying and 90 partial reduction of the refuse.

Combustion is maintained in the incinerator by a continuous supply of air, which is delivered to the combustion zone in the following manner:

The draft created by the chimney manifestly draws the products of combustion through the outlet 27, downwardly through the space 28, and thence through the passages 29 and 31, to the chimney. The air supply to the combustion zone originates in the chute 16, the chimney draft being sufficient to create a sub-atmospheric pressure therein, thus drawing the air from the rooms 105 through the refuse discharge openings above. Although these doors are closed except when the refuse is being emptied, as a practical matter they are not air tight, so that there is always sufficient leakage of air to maintain a constant down draft in the chute. The air thus drawn through the chute 16, is bypassed through the opening 21 to the flue 23, and thence carried forwardly beneath the incinerator, entering the ash pit at its forward end. In the operation of the incinerator the ash door is kept closed, except for emptying the ashes, so that the only source of air supply is through the flue 23. Manifestly odors will rise from the accumulation of garbage at the base of the chute, but these are carried through the grated opening 21, just above and thence through the incinerator to the chimney. Furthermore, due to the down draft in the chute 16, 110

these odors cannot rise above the opening 21, to the floors above and as a result no trace of odors can be detected by reason of air escaping or forced through the refuse doors. In other words, there is a constant suction in the chute tending to draw the air from the rooms, particularly when the doors are momentarily opened, to deposit the refuse. By the closing off of all air 10 inlets to the combustion chamber other than through the flue 23, the draft is maintained at all times although manifestly is increased materially when a fire is being maintained in the incinerator. In this manner the disposal and consummation of refuse and garbage can be successfully accomplished with the complete elimination of odors, this being primarily the result of the separate flue, which by-passes the air from 20 the chute to the combustion zone, and indirectly connects the chute with the chimney, thereby maintaining a constant circulation or down-draft in the chute. Other improvements in structure also contribute to the results herein set forth, all of which are disclosed in more concise form in the appended 25 claims.

I claim as my invention:

1. An incinerator comprising a combustion chamber, a grate therein for supporting a bed of fuel, a chimney communicating with said combustion chamber, a refuse chute opening into said combustion chamber and a duct communicating with said

chute above the opening into said combustion chamber and leading to the space beneath the grate. 35

2. An incinerator comprising a combustion chamber having a grate in the forward portion, a hearth at the rear of said grate 40 and an outlet flue leading from said combustion zone, to the atmosphere, a refuse chute opening into said combustion chamber and above said hearth, and a by-pass duct opening from said chute above the opening 45 thereof to said combustion chamber and leading to said combustion chamber adjacent said grate.

3. An incinerator comprising a combustion chamber having a grate in the forward 50 portion and an ash pit below said grate, a hearth at the rear of said grate, an outlet duct leading downwardly from the upper portion of said combustion chamber and connected with transverse passages beneath 55 said hearth, a chimney connecting with said passages, a chute opening into said chamber above said hearth, a gate mounted above said hearth and adapted to be swung into positions to open and close the lower end of 60 said chute, and a duct communicating with said chute at a predetermined distance above its lower end, and extending exterior of said chamber to the ash pit. 65

In witness whereof, I hereunto subscribe 66 my name this first day of August, A. D., 1923.

GEORGE SUTCLIFFE.
